ACCESSORIES CONTAINER

Edwin H. Koehler, New York, N. Y.

Application December 19, 1933, Serial No. 703,039

17 Claims. (Cl. 206—41)

My invention relates to containers for cigarettes and other articles and refers particularly to such containers in which the opening and closing of the container protrudes or withdraws the article, and in which these two operations are co-ordinated.

Pocket cigarette cases are intended to protect the cigarettes against being crushed or broken, to conserve their flavor and to render their use convenient. While the device of my invention is more particularly intended for use as a cigarette container to be carried upon the person, it is capable of other uses.

There are various kinds of metal pocket cigarette cases or containers, the larger number of which are more or less inconvenient for use, while some are of complicated construction, expensive to manufacture and liable to become inoperative.

The device of my invention is simple in construction, economical to manufacture, unlikely to become inoperative and is readily operated by one hand. More particular advantages and valuable attributes of my invention will clearly appear from the following description taken in connection with the accompanying drawings.

In general, the device of my invention comprises a pair of similar laterally spaced parallel flexible bands or the like, guided within an outer casing, these bands carrying between them a flexible cover for the casing and also carrying a receptacle forming a carrier for cigarettes, or other articles, these connected bands thus being adapted to have unitary movement. The relation and arrangement of the operating parts are such that one movement imparted to these bands will cause the contained cigarettes to be presented in a readily accessible position for removal and use, and another movement of such bands will be effective to withdraw the cigarettes into the casing, while at the same time and by the same respective movements of these bands, the flexible cover for the casing is opened and again closed.

My invention further includes various features of construction and combination of parts, as will appear from the following description of one form of the device which is illustrated in the accompanying drawings, in which similar parts are designated by similar reference numerals.

Figure 1 is a front perspective view of a container embodying my invention showing such container in its closed condition.

Figure 2 is a similar view showing the open condition of the container of my invention.

Figure 3 is an enlarged broken vertical section taken on the line 3—3 of Figure 4 with the container shown in its closed condition as in Figure 1.

Figure 4 is a central vertical section on the line 4—4 of Figure 3.

Figure 5 is a horizontal transverse section taken on the stepped line 5—5 of Figure 3.

Figure 6 is a vertical section substantially similar to Figure 4 but showing the container in its open condition as in Figure 2.

Figure 7 is a perspective view of an inner receptacle-carrying operating structure, with its movable parts positioned as in Figure 6.

Figure 8 is a similar view of an inner receptacle forming an article carrier which is disposed within and is carried by the operating structure shown in Figure 7.

Figure 9 is a perspective view of a bottom closure for the outer casing of the container.

Figure 10 is a perspective view of an operating stud, the outer end of which is adapted to form a finger piece for opening and closing the container as shown in Figures 1, 2, 4, 5 and 6.

The particular form of the device of my invention illustrated in the accompanying drawings comprises an inner operating structure or member which is separately shown in Figure 7. This structure comprises a pair of similar end frames, each of which is of vertically elongated U-shape having side arms 10—10 and an intermediate lower connecting portion 11. The vertical arms 10—10 of each of these U-shaped frames are connected together by a pair of upper and lower journal pins 12—12 with the upper one of these pins adjacent to the upper ends of the arms and with the lower journal pin substantially spaced above the arm-connecting portion 11.

Similar pulleys 13—13 are journaled respectively upon the upper and lower pins 12—12 between the frame arms 10—10. Each of these pulleys 13—13 has a guide flange 14. It will be noted that in each instance these pulley flanges 14—14 are disposed adjacent to the arm 10 which is laterally at the outer side of the inner operating structure as a whole.

A pair of similar endless flexible members, such as metallic bands 15—15, run respectively over each pair of pulleys 13—13. At the front these bands are connected together by means of a horizontal cross bar 16 secured thereto at its ends. At another point, in suitably spaced relation from this cross bar 16 along the bands 15—15, shown in Figure 7 as being at the back, these bands 15—15 are similarly connected together by a flexible transverse cover strip 17 adapted to form a movable cover for an outer casing to be described later.

A rectangular box-like receptacle, shown separately in Figure 8, is provided to receive and form a carrier for cigarettes 18—18, or other articles, to extend upwardly beyond the open top of this receptacle as shown in Figures 3, 4 and 6. This open-top receptacle has a front wall 19, a rear wall 20, similar end walls 21, 21 and a bottom 22. It is fixedly carried by the cross bar 16.

at the rear thereof with the outer faces of its end walls 21-21 slightly spaced from the adjacent faces of the opposed inner arms 10-10 of the respective U-shaped end frames, so as to be 5 freely movable between these frame arms longitudinally thereof, which is vertically in the position of the device shown in Figures 1, 2, 3, 4 and 6.

This receptacle is fixedly attached to the cross 10 bar 16 by means of tongues or prongs 23-23 which respectively pass outwardly through apertures 24-24 through the bar 16. These tongues 23-23 extend forwardly from the front wall 19 and are turned over at the front of the bar 16, 15 as shown in Figure 3.

The front wall 19 of the receptacle has through it a circular opening 25 midway of its width in lateral or horizontal alignment with the attaching tongues 23, 23, while the transverse or horizontal bar 16 has through it a smaller circular opening 26 in registering alignment with the opening 25 for the reception of an operating stud to be described later.

With the above described article receptacle thus 25 fixedly assembled within the above described operating structure the resulting instrumentality or mechanism forming an inner part of the device, is ready to be assembled within an outer casing. This outer casing comprises a flat front wall 27, 30 a similar rear wall 28, a rounded connecting top wall 29, similar side walls 30, 30 and is originally open at its lower end or bottom, which is to be closed by a bottom, described later.

The rounded top wall 29 is cut away to provide 35 a large opening 31, shown as of a width extending into alignment with the front and rear walls 27 and 28 and as of a transverse length substantially the same as the length of the receptacle between the outer faces of its end walls 21-21. Thus the top of this casing is open throughout 40 the major portion of its extent. The front casing wall 27 has through it a slotted opening 32 extending parallel with and midway between its side walls 30-30. The above described assembled inner part of the device is assembled within 45 the outer casing by inserting it therein through the open lower end of the latter. The relative dimensions are such that the laterally outer arms 10-10 of this inner part fit snugly against the inner faces of the side walls 30-30 of this casing, but slide longitudinally thereon during the 50 assembling operation.

An operating stud 33 having a relatively thin head 34 may now be passed to the inside of the 55 device through the top opening 31 and inserted through the receptacle opening 25 and the cross bar opening 26 to project to the outside of the casing wall 27 through its slot 32. The head 34 of the stud is received into the opening 25 in 60 countersunk relation so as not to project beyond the inner face of the receptacle wall 19 and may be substantially flush with the latter, as shown in Figure 4. The outer end of this stud 33 forms a finger piece and carries an annular outer head 65 member 35 which may be secured upon the stud 33 by riveting the latter, as shown in Figures 1, 2, 4, 5 and 6.

The movable cover piece or shield member 17 for the casing may be made from any suitable 70 sufficiently flexible sheet material, for example, celluloid or metal. Adjacent its corners this casing cover is securely attached to the tapes or bands 15-15, as is shown in Figure 3 for two of these corners at the opposite ends of this casing 75 cover. The ends of this cover sheet or strip 17

are desirably wider than its middle portion and it is shown as having a gradual concave curve along its edges between its ends, as is clearly shown in Figures 3 and 7. However, the narrower middle portion of this casing cover is wider 5 than the width of the larger slotted opening 31 in the top of the casing, as will be seen in Figures 3 and 4. The above noted shape of this flexible casing cover or shield member 17 strengthens its attachment to the endless bands 10 15-15, strengthens this cover itself and also facilitates its operation in its movement between its open and closed positions.

It is to be noted of the particular construction shown that the two outermost arms 10-10 of 15 the substantially U-shaped end frames are extended upwardly beyond the adjacent upper roller pivots 12-12 to form extensions 36-36 respectively. The upper ends of these extensions 36-36 project upwardly slightly beyond the adjacent roller flanges 14-14 and are adapted to abut against the casing top wall 29, as is clearly shown in Figures 3, 4 and 7. Thus it is rendered impossible for either the traveling bands 15-15 or the flexible casing cover 17 to come into 25 rubbing contact with the casing top 29.

In assembling the previously assembled inner part of the device within the outer casing part or housing, the inward sliding movement of this inner part will be stopped by the projecting 30 ends of the frame extensions 36, 36 abutting against the inner side of the casing top wall 29. The rounded contour of these extensions 36, 36 and of the casing top 29 centers the upper ends of the arms 10, 10 in a front and rear direction 35 within the outer casing. The joining members 11, 11 for the frame arms 10, 10 will now be slightly inward beyond the lower edges of the walls of this outer casing, as shown in Figures 3, 4 and 6.

The bottom end of this main outer casing part 40 may now be closed by means of a casing bottom 37, shown separately in Figure 9. This casing bottom 37 is provided with upturned front and rear flanges 38, 38 and also with end flanges 39, 45 39. Each of these end flanges 39, 39 has its middle portion cut away so as to provide respective end notches 40, 40 which are of the same width as the arms 10, 10 and their connectors 11, 11. The casing bottom 37 is of such 50 dimensions that its flanges 38, 38 and 39, 39 will fit snugly within the lower end of the outer casing part between its front and rear walls 27, 28 and similarly between its side walls 30, 30.

When the casing bottom 37 has been thus placed 55 in position its outer face will be flush with the lower edges of the casing walls 27, 28 and 30, 30. At the same time the inner face of this bottom closure 37 adjacent its end notches 40, 40 will be in abutting engagement with the lower face of the 60 frame arm connectors 11, 11 which then will be centered from front to rear within these notches 40, 40 in the end flanges 39, 39 of the bottom 37, this assembled relation being clearly shown in Figures 3, 4 and 6 of the drawings. This bottom 65 closure 37 may now be securely fastened in place in any suitable way, such as by soldering.

The operation is as follows:—

Let it be assumed that the container device is in its closed condition with its movable top 70 cover 17 then completely closing the top casing opening 31 and with the contained cigarettes 18, 18 then fully housed within the closed casing as shown in Figures 1, 3 and 4. The finger piece, comprising the operating stud 33 together with 75

its attached outer head 35, is now at the lower end of the slot 32 in the front casing wall 27. If now the operating member forming the finger piece is moved upwardly, the cross bar 16 will 5 concomitantly move the forward stretches or runs of the bands 15, 15 in an upward direction, the rear stretches or runs of these bands thus being moved downwardly, thereby moving the flexible casing cover 17 edgewise rearwardly and down- 10 wardly.

When the finger piece stud 33 has reached the upper end of the slot 32, the flexible casing cover 17 will then be at a retracted lower position at the back of the casing alongside the inner face of 15 its rear wall 28, as shown in Figure 6 and indicated in Figure 7. At the same time and by 20 this same movement the cross bar 16 will raise the cigarette-containing receptacle to an upper position in which the upper edges of its front and rear walls 19 and 20 are respectively flush with the upper edges of the front and rear walls 27 and 28 of the outer casing.

The cigarettes 18, 18 will now have their upper 25 end portions projecting through the now un- covered opening 31, as shown in both of Figures 2 and 6, so that thus these cigarettes may be easily removed. A reverse or downward movement of the finger piece stud 33 will be effective to lower the cigarette-carrying receptacle and 30 at the same time to move the flexible cover 17 edgewise upwardly and thence forwardly across the casing opening 31, thereby closing the latter, with the cigarettes 18, 18 then completely housed in the closed casing, as shown in Figures 1 and 3, 35 the bottom 22 of the cigarette-carrying receptacle then being in abutting engagement with the casing bottom 37, as shown in Figures 3 and 4.

It will now be evident that by the manual movement of a single operating part, which is 40 the operating stud 33 forming the finger piece, in one direction, which is upward in the construction shown, the container casing will be opened at its top and the contained articles, such as the cigarettes 18, 18, will be thrust out 45 through this open top so as to be readily grasped and removed, while a downward movement manually imparted to this finger piece 33 will withdraw these cigarettes, or other contained articles, into the casing and close the latter.

50 In this connection it is to be noted that the operating bar 16 serves a double purpose or performs two functions, in the particular form of the device of my invention illustrated in the drawings. Thus this single operating bar 16 directly moves the article-carrying receptacle in 55 raising or lowering the latter and at the same time this bar 16, through the intermediary of the endless traveling bands 15-15, is effective to move the flexible casing cover 17 in either direction 60 between its open and closed positions.

While the above described device of my invention is shown in the drawings as used for a cigarette case, it is now evident that this device is 65 equally well adapted for other uses where a similar manner of operation is desired. For example, among other articles which may be similarly carried within the movable receptacle are cards or the like, a small book, a cake of soap.

In the specification and claims, when I employ 70 such terms as "top" and "bottom", "upwardly" and "downwardly", or similar expressions, reference is had merely to the position of the device as shown in the drawings, since obviously the device may have some different position. Also by 75 "portable" I mean a device which may be held

in the hand and readily carried upon the person, in a pocket or otherwise, when so desired.

It is to be further noted, particularly from Figures 1 and 2, that the device of my invention is compact and self-contained, while also it has a 5 neat and pleasing appearance.

I do not limit myself to the particular size, shape, number, arrangement or material of parts as shown and described, as these are given simply as a means for clearly explaining my invention. 10

Furthermore, it is obvious that various modifications may be made in the construction shown in the drawings and above particularly described, within the principle and scope of my invention as defined in the appended claims. 15

What I claim is:—

1. In a device of the character described, in combination, a casing having an open end and a closed end, a pair of spaced parallel endless flexible members guided within said casing for longitudinal traveling movement therein, a cover carried by said members capable of movement across the open end of said casing for opening and closing the latter, an article carrier carried by said members in interposed relation between the latter and capable of longitudinal movement within said casing, including movement beyond said flexible members toward the closed end of said casing, and exterior operating means capable of moving said members concomitantly. 20

2. In a device of the character described, in combination, a casing having an open end and a closed end, a pair of spaced parallel endless flexible bands guided within said casing for longitudinal traveling movement therein, a cover carried by said bands capable of movement across the open end of said casing for opening and closing the latter, an article carrier carried by said bands in interposed relation between the latter and capable of longitudinal movement within said casing, including movement beyond said flexible bands toward the closed end of said casing, and exterior operating means capable of moving said bands concomitantly. 35

3. In a device of the character described, in combination, a casing having an open end and a closed end, a pair of spaced parallel endless flexible members guided within said casing for longitudinal traveling movement therein, a flexible cover carried by said members capable of movement across the open end of said casing for opening and closing the latter, an article carrier carried by said members in interposed relation between the latter and capable of longitudinal movement within said casing, including movement beyond said flexible members toward the closed end of said casing, and exterior operating means capable of moving said members concomitantly. 45

4. In a device of the character described, in combination, a casing having an open end and a closed end, a pair of spaced parallel endless flexible bands guided within said casing for longitudinal traveling movement therein, a flexible cover carried by said bands capable of movement across the open end of said casing for opening and closing the latter, an article carrier carried by said bands and in interposed relation between the latter and capable of longitudinal movement within said casing, including movement beyond said flexible bands toward the closed end of said casing, and exterior operating means capable of moving said bands concomitantly. 60

5. In a device of the character described, in combination, a casing having an open end and a closed 65

end, a pair of spaced parallel endless flexible members guided within said casing for longitudinal traveling movement therein, a plurality of pulleys within said casing forming guides for said flexible members, a cover carried by said members capable of movement across the open end of said casing for opening and closing the latter, an article carrier carried by said members and capable of longitudinal movement within said casing, and exterior operating means capable of moving said members concomitantly.

6. In a device of the character described, in combination, a casing having an open end and a closed end, a pair of spaced parallel endless flexible members guided within said casing for longitudinal traveling movement therein, a fixed frame member within said casing for each of said flexible members, a set of guide pulleys for each of said flexible members mounted upon the respective said frame members, a cover carried by said members capable of movement across the open end of said casing for opening and closing the latter, an article carrier carried by said members and capable of longitudinal movement within said casing, and exterior operating means capable of moving said members concomitantly.

7. In a device of the character described, in combination, a casing having an open end and a closed end and a longitudinal slot, a pair of spaced parallel endless flexible members guided within said casing for longitudinal traveling movement therein, a cover carried by said members capable of movement across the open end of said casing for opening and closing the latter, an article carrier carried by said members in interposed relation between the latter and capable of longitudinal movement within said casing, including movement beyond said flexible members toward the closed end of said casing, and exterior operating means capable of moving said members concomitantly extending through said slot and capable of longitudinal movement therein.

8. In a device of the character described, in combination, a casing having an open end and a closed end and a longitudinal slot, a pair of spaced parallel endless flexible members guided within said casing for longitudinal traveling movement therein, a cover carried by said members capable of movement relatively to the open end of said casing for opening and closing the latter, an article carrier carried by said members and capable of longitudinal movement within said casing, said endless members being spaced laterally beyond said article carrier and said carrier having a path of longitudinal movement between said endless members parallel therewith, and exterior operating means extending through said slot and capable of longitudinal movement therein and fixedly connected to said carrier to move in the same direction therewith.

9. In a readily portable refillable container for one or more articles to be removed therefrom for use, in combination, a substantially rectangular flattened outer casing closed at its lower end and open at its upper end, a flexible cover member adapted to be moved edgewise across the upper end of said outer casing for opening and closing the latter, a substantially rectangular flattened carrier member open at its top and capable of upward and downward movement within said casing, a pair of movable spaced parallel endless flexible members connecting said movable cover and said movable carrier member together for concomitant movement, each of said flexible members having front and rear runs connected

together by upper and lower bights thereof of which said upper bights are immediately adjacent to the open upper end of said casing, a guide fixedly mounted in said casing for each of the bights of said flexible members, and operating means including a finger piece exposed at the outside of said casing and connected with said movable elements for thereby moving the latter concomitantly.

10. In a readily portable refillable container for one or more articles to be removed therefrom for use, in combination, a substantially rectangular flattened outer casing closed at its lower end and open at its upper end, a flexible cover member adapted to be moved edgewise across the upper end of said outer casing for opening and closing the latter, a substantially rectangular flattened carrier member open at its top and capable of upward and downward movement within said casing, a pair of movable spaced parallel endless flexible members connecting said movable cover and said movable carrier member together for concomitant movement, each of said flexible members having front and rear runs connected together by upper and lower bights thereof of which said upper bights are immediately adjacent to the open upper end of said casing, a guide fixedly mounted in said casing for each of the bights of said flexible members, and operating means including a finger piece exposed at the outside of said casing and connected with said movable elements for thereby moving the latter concomitantly, said finger piece being movable forward and back and the relationship of said movable members being such that when said finger piece is moved in one direction the top of said casing will be uncovered and the contained articles raised to an accessible position while the movement of said finger piece in a reverse direction will withdraw said articles into the casing and close the open top of the latter.

11. In a readily portable refillable container for one or more articles to be removed therefrom for use, in combination, a substantially rectangular flattened outer casing closed at its lower end and open at its upper end, a flexible cover member adapted to be moved edgewise relatively to the upper end of said outer casing for opening and closing the latter, a substantially rectangular flattened carrier member open at its top and capable of upward and downward movement within said casing, a pair of movable spaced parallel endless flexible members connecting said movable cover and said movable carrier member together for concomitant movement, each of said flexible members having vertical runs connected together by upper and lower bights thereof of which said lower bights are spaced above the closed lower end of said casing, a guide fixedly mounted in said casing for each of the bights of said flexible members, said carrier member being movable upwardly and downwardly between and beyond the guides for the lower bights of said endless members, and operating means including a finger piece exposed at the outside of said casing and connected with said endless members for thereby moving the latter concomitantly.

12. In a readily portable refillable container for one or more articles to be removed therefrom for use, in combination, a substantially rectangular flattened outer casing closed at its lower end and open at its upper end, a flexible cover member adapted to be moved edgewise relatively to the upper end of said outer casing for opening and closing the latter, a substantially rectangular flat-

- tened carrier member open at its top and capable of upward and downward movement within said casing, a pair of movable spaced parallel endless flexible members connecting said movable cover and said movable carrier member together for concomitant movement, each of said flexible members having vertical runs connected together by upper and lower bights thereof of which said lower bights are spaced above the closed lower end of said casing, a guide fixedly mounted in said casing for each of the bights of said flexible members, said carrier member being movable upwardly and downwardly between and beyond the guides for the lower bights of said endless members, and operating means including a finger piece exposed at the outside of said casing and connected with said endless members for thereby moving the latter concomitantly, said finger piece being movable upwardly and downwardly and the relationship of said movable members being such that when said finger piece is moved upwardly said cover member will be moved in a direction to uncover the top of said casing and said carrier member will be raised in said casing while the movement of said finger piece in a downward direction will lower said carrier member in said casing and move said cover member in a direction to close the open top of said casing.
13. In a readily portable refillable container for one or more articles to be removed therefrom for use, in combination, a substantially rectangular flattened outer casing closed at its lower end and open at its upper end, a flexible cover member adapted to be moved edgewise relatively to the upper end of said outer casing for opening and closing the latter, said cover member being movable rearwardly and downwardly for opening said casing and being movable upwardly and forwardly for closing said casing, a substantially rectangular flattened receptacle open at its top and capable of upward and downward movement within said casing, a pair of movable spaced parallel endless flexible members connecting said movable cover and said movable receptacle together for concomitant movement, each of said flexible members having front and rear runs connected together by upper and lower bights thereof, a guide fixedly mounted in said casing for each of the bights of said flexible members, said endless members and their respective said guides being spaced laterally beyond said carrier member with the latter extending flatwise between them and having a path of movement between the respective said guides and between said endless members parallel with the latter, said receptacle being fixedly carried by the front runs of said flexible members, and a finger piece exposed at the outside of said casing at the front and fixedly connected to said receptacle thereby to move the latter in the same direction that said finger piece is moved.
14. In a device of the character described, in combination, a casing having an open end and a closed end, a pair of spaced parallel endless flexible members guided within said casing for longitudinal traveling movement therein, a cover carried by said members capable of movement across the open end of said casing for opening and closing the latter, an article carrier carried by said members and capable of longitudinal
- movement within said casing, said endless members being spaced laterally beyond said article carrier and said carrier having a path of longitudinal movement between said endless members parallel therewith, and exterior operating means capable of moving said members concomitantly.
15. In a device of the character described, in combination, a casing having an open end and a closed end, a pair of spaced parallel endless flexible bands guided within said casing for longitudinal traveling movement therein, a flexible cover carried by said bands capable of movement across the open end of said casing for opening and closing the latter, an article carrier carried by said bands and capable of longitudinal movement within said casing, said endless bands being spaced laterally beyond said article carrier and said carrier having a path of longitudinal movement between said endless bands parallel therewith, and exterior operating means capable of moving said bands concomitantly.
16. In a device of the character described, in combination, a casing having an open end and a closed end, a pair of spaced parallel endless flexible members guided within said casing for longitudinal traveling movement therein, a fixed frame member within said casing for each of said flexible members, a set of guide pulleys for each of said flexible members mounted upon the respective said frame members, a cover carried by said members capable of movement across the open end of said casing for opening and closing the latter, an article carrier carried by said members and capable of longitudinal movement within said casing, said endless members and their sets of guide pulleys being spaced laterally beyond said article carrier with the latter extending between them and having a path of movement between said sets of guide pulleys and between said endless members parallel with the latter, and exterior operating means capable of moving said members concomitantly.
17. In a readily portable refillable container for one or more articles to be removed therefrom for use, in combination, a substantially rectangular flattened outer casing closed at its lower end and open at its upper end, a flexible cover member adapted to be moved edgewise relatively to the upper end of said outer casing for opening and closing the latter, a substantially rectangular flattened carrier member open at its top and capable of upward and downward movement within said casing, a pair of movable spaced parallel endless flexible members connecting said movable cover and said movable carrier member together for concomitant movement, each of said flexible members having vertical run connected together by upper and lower bights thereof, a guide fixedly mounted in said casing for each of the bights of said flexible members, said endless members and their respective said guides being spaced laterally beyond said carrier member with the latter extending flatwise between them and having a path of movement between the respective said guides and between said endless members parallel with the latter, and operating means including a finger piece exposed at the outside of said casing and connected with said endless members for thereby moving the latter concomitantly.

EDWIN H. KOEHLER.
